DESIGN FOR A SHOE OR SIMILAR ARTICLE

Oswald M. Pick, Chicago, Ill., assignor to The Florsheim Shoe Company, Chicago, Ill., a corporation of Illinois

Application October 29, 1937, Serial No. 72,515

Term of patent 7 years

To all whom it may concern:

Be it known that I, Oswald M. Pick, a citizen of the United States and a resident of the city of Chicago, in the county of Cook and State of Illinois, have invented a new, original, and ornamental Design for a Shoe or Similar Article, of which the following is a specification, reference being had to the accompanying drawing, forming a part thereof.

On the drawing:

I claim:

The ornamental design for a shoe or similar article as shown,

OSWALD M. PICK.
